(57) **CLAIM**

The ornamental design for a support stand for a digital microscope, as shown and described.

DESCRIPTION

FIG. 1 is a front perspective view of a support stand for a digital microscope showing our new design;

FIG. 2 is a rear perspective view thereof;

FIG. 3 is a front view thereof;

FIG. 4 is a rear view thereof;

FIG. 5 is a top plan view thereof;

FIG. 6 is a right side view thereof;

FIG. 7 is a left side view thereof;

FIG. 8 is an enlarged cross-sectional view taken along line 8-8 in FIG. 3;

FIG. 9 is an enlarged cross-sectional view taken along line 9-9 in FIG. 3;

FIG. 10 is an enlarged view of the portion indicated by line 10-10 in FIG. 1;

FIG. 11 is an enlarged view of the portion indicated by line 11-11 in FIG. 2;

FIG. 12 is an enlarged view of the portion indicated by line 12-12 in FIG. 3;

FIG. 13 is an enlarged view of the portion indicated by line 13-13- in FIG. 5;

FIG. 14 is an enlarged view of the portion indicated by line 14-14 in FIG. 8;

FIG. 15 is an enlarged view of the portion indicated by line 15-15 in FIG. 9;

FIG. 16 is a reduced cross-sectional view of the knob shown separately for ease of illustration and cross-sectional view taken along line 16-16 in FIG. 12; and,

FIG. 17 is a perspective view showing the article in use.

The features shown in broken lines in the drawings depict environmental subject matter only and form no part of the claimed design. The dot-dashed lines denote the boundary of the claim and form no part of the claimed design.
